UNITED STATES PATENT OFFICE

2,047,496

AIRCRAFT SAFETY APPARATUS

Ralph Seitz, Chicago, Ill.

Application February 2, 1932, Serial No. 590,467

4 Claims. (Cl. 244—21)

This invention relates to certain novel improvements in aircraft safety apparatus, and has for its principal object the provision of an improved construction of this character which will be highly efficient in use and economical in manufacture.

It is the primary object of this invention to provide new and efficient safety apparatus for use by the occupant of an aircraft.

Other objects of the invention are: to provide a novel aircraft chair and detachable back rest or panel therefor; to provide new, improved and efficient means for releasably holding a parachute in folded position to the panel or back rest of the chair; to provide new and efficient means for releasably attaching the panel or back rest to said chair; to provide new and effective means for releasing the parachute from said holding means and out of folded position; and to provide the novel combination of elements hereinafter described and set forth in the appended claims.

Other objects will appear hereinafter.

The invention consists in the novel combination and arrangement of parts to be hereinafter described and claimed.

The invention will be best understood by reference to the accompanying drawing, showing the preferred form of construction and in which:

Fig. 1 is a fragmentary sectional view of an airplane showing the invention in side elevation;

Fig. 2 is a front elevational view of the invention;

Fig. 3 is a perspective detail view of a chair and panel housing embodied in the invention;

Fig. 4 is a perspective view of the seat panel and parachute-holding and releasing means;

Fig. 5 is a plan view of the seat panel and parachute-holding means; and

Fig. 6 is a perspective view of the parachute-releasing means.

In the drawing, which illustrates a preferred and practical embodiment of the invention, 10 indicates a fragment of a conventional type of aircraft having a floor 11. On the floor 11 I stationarily mount a chair 12 which includes a conventional seat 13. The chair 12 includes a pair of upright legs 14 in the upper end of each of which is provided a slot 15 and extending between the legs 14 is a brace rod 16 which is provided with a pair of spaced slots 17.

The back rest or panel for the chair 12 is indicated generally at 18 and includes a frame 19 to which is attached a cushion 20. Attached to the frame 19 is a body harness 21 which includes body-encircling straps 22 and 22a to which may be attached other straps 24; said straps carry-

ing shrouds 23 which are attached to the parachute 25. The parachute 25 is normally folded into a small bundle which has its ends inserted under straps 26 that are attached to frame 19.

Attached to frame 19 are projecting elements 5 27 and 28 which are receivable, respectively, in the slots 15 and 17 in chair 12 when the person is seated in said chair 12.

A casing 29 having an open front 30 is attached to the legs 14 of the chair 12, in any suitable manner, and this casing 29 receives the panel 18 when the occupant is in the chair 12. The casing 29 has a hinged top 31.

Retaining the ends of the parachute bundle under straps 26 is a rod 32 which is inserted 15 through rings 31 on the straps 26. Hinged, as at 33, to the rod 32 is an arm 34 having a handle 35; the arm 34 and handle 35 projecting over the top of panel 18. The arm 34 and rod 32 are urged toward each other by a spring 36. 20

The ends of the parachute bundle are tucked under the straps 26 and the rod 32 is inserted through the rings 31 on straps 26. The projecting elements 27 and 28 are then inserted into the slots 15 and 17 respectively and the panel 18 into 25 the casing 29 through the open side 30 of the latter, whereupon the harness 21 may be placed loosely on the body as in dotted line position of Fig. 1. The arm 34 is at this time folded back substantially parallel to arm 32, as in Fig. 1. 30 In case of emergency the occupant of the chair attaches the separable straps of the body harness about his person, rises and thereby lifts the elements 27 and 28 out of the slots 15 and 17, respectively, while at the same time the hinged door 31 of casing 29 is opened by upward movement of panel 18 whereupon the spring 36 throws the arm 34 into dotted line position of Fig. 1 and the person then makes his exit from the aircraft 10 through an outlet such as 37. He then grasps and lifts upwardly on handle 35 and thereby slides the rod 32 upwardly out of the rings 31 on straps 26, whereupon air currents flowing in and about the parachute bundle and between 35 the same and panel 18 force the ends of the parachute out from under the straps 26 and the parachute is thus opened. 40

While I have illustrated and described the preferred form of construction for carrying my 50 invention into effect, this is capable of variation and modification, without departing from the spirit of the invention. I, therefore, do not wish to be limited to the precise details of construction set forth, but desire to avail myself of such 55

variations and modifications as come within the scope of the appended claims.

Having thus described my invention what I claim as new and desire to protect by Letters 5 Patent is:

1. Aircraft safety apparatus, comprising the combination of a chair including upright legs, a casing attached to said chair having an open side and a hinged top, a detachable back rest or 10 panel for said chair receivable in said casing through said open side and releasable therefrom through said hinged top, means cooperating with said legs for releasably latching said panel thereto, a body harness attached to said panel, a para- 15 chute, means for releasably holding said parachute in folded position on said panel, and means for releasing said parachute from said parachute-holding means.
2. In an aircraft safety device, a chair having 20 a detachable seat back, a casing fastened to the chair, a parachute arranged in folded condition upon the back side of said seat back and within said casing, said seat back having straps fastened thereto and arranged for encircling the para- 25 chute to hold the same in its folded condition adjacent the seat back, said straps being provided with ring means, a rod arranged to pass through said ring means for holding the straps in a supporting condition about the parachute, a manually 30 operable member pivotally connected with said rod spring means tending to swing said manually operable member across the shoulder of a person leaning against the said seat back, said manually operable member being normally positioned with-

in said casing and positioned out of reach of the occupant of the chair by its engagement with the casing, and means for connecting the seat back with the occupant, to permit the seat back to be removed from the chair and out of said casing, 5 said manually operable member swinging over the shoulder of the occupant when the manually operable member is moved out of engagement with the casing, to permit the occupant to pull the rod out of said ring means for releasing the para- 10 chute.

3. An aircraft safety device comprising a seat including a back, said back being detachably connected with the seat, a housing carried by the seat adjacent said back, a parachute releasably 15 connected with said back and being arranged within said housing, and means for connecting the back with an occupant of the seat, said back being disconnected from the seat when the occupant leaves the seat and said parachute being re- 20 moved from the housing with the detachment of the back from the seat.

4. An airplane safety apparatus comprising a chair including a detachable back rest, means for fastening the back rest to an occupant of the 25 chair, a normally folded parachute, means for detachably connecting the parachute with said back rest, and a housing carried by the chair and enclosing the parachute, said parachute being removed from the housing when the back rest is 30 separated from the chair through the movement of the occupant therefrom.

RALPH SEITZ.
